Primary Examiner — Rosemary K Tarcza(57) **CLAIM**

The ornamental design for a portable charging device, as shown and described.

DESCRIPTION

FIG. 1 is an isometric top view of a portable charging device in accordance with the present invention;

FIG. 2 is an isometric bottom view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a front-side perspective view thereof, shown in an environment of use with a cord and electronic device. The broken lines shown illustrate environmental structure or portions of the portable charging device which form no part of the claimed design.
